UNITED STATES PATENT OFFICE

FRANK A. TALBOT, OF BALTIMORE, MARYLAND, ASSIGNOR OF ONE-HALF TO WILLIAM B. W. MANN, OF BALTIMORE, MARYLAND

NONREFILLABLE RECEPTACLE

Application filed September 25, 1931. Serial No. 565,155.

This invention relates to improvements in receptacles of the type to be used only once, that is, of the kind which cannot be refilled through the same passageway employed in the initial filling.

The primary object of the invention is to furnish for this purpose improved liquid and air passageways combined with suitable baffle means and a valve, all so constructed that 10 the device may be manufactured at relatively small expense, and which will be practical and durable in action.

Another object is to provide a receptacle of the non-refillable type, in which the valve 15 which prevents refilling, is initially held off its seat by a suitable retainer; said retainer when the closing plug of the receptacle is inserted, functioning to release the valve retaining means, whereby the valve automatically seats, when the closure plug is attached to the receptacle.

A further object is to furnish a device of this character, in which the valve may be initially held off its seat by magnetically operated means; such means, when actuated by 25 a magnet, functioning to move out of obstructing position so that the valve may automatically close.

A still further object is to provide a device of this kind, having the valve initially held off its seat by distortable pins or the like, which may be distorted by movement of the 30 passageway baffle, the latter being actuated either by magnetic or mechanical means.

A further object is to provide such structures with means to facilitate their attachment to the conventional pump used at the top of an oil dispensing drum or the like, whereby as the liquid is pumped from the 35 drum or barrel, air may enter the latter through the pump to displace the oil discharged.

With the foregoing objects outlined and with other objects in view which will appear 45 as the description proceeds, the invention consists in the novel features hereinafter described in detail, illustrated in the accompanying drawings, and more particularly pointed out in the appended claims.

In the drawings,

Fig. 1 is a vertical sectional view of one form of the device, as employed in connection with a non-refillable drum.

Fig. 2 is a horizontal sectional view of the same on the line 2-2 of Fig. 1. 55

Fig. 3 is a vertical sectional view of a modification.

Fig. 4 is a similar view of another modification, and with the top ring removed to facilitate illustration. 60

Fig. 5 is a horizontal sectional view on the line 5-5 of Fig. 4.

Fig. 6 is a vertical sectional view of a portion of an oil drum and a dispensing pump, and illustrating an adapter by which the conventional pump may be used with any one of the forms of my invention disclosed herein. 65

Fig. 7 is a top plan view of the top ring of any one of the forms of the invention illustrated. 70

In the embodiment of the invention illustrated in Figs. 1 and 2, 8 designates the shell of the improved structure which may be shaped at its bottom as shown at 9, to be connected to the down pipe 10 which extends from the top to the bottom of an oil drum. In forming the shell from sheet metal, it is preferably provided with an annular trough, as shown at 11, for a purpose hereinafter described. 75

The upper end of the shell is crimped, as shown at 12, to an annular ledge 13 which is positioned below the extreme upper surface 14 of the top ring 15 of the device, so that channels or grooves 16 radially placed in said upper surface will function to admit air to the drum beneath the head 17 of the latter, while oil is being withdrawn from the drum. 80

In accordance with the invention, the top part of the ring 15, as best shown in Fig. 7, is preferably of octagonal shape, as indicated at 18, and this specially shaped aperture has its wall undercut or recessed as at 19 in Fig. 1. This permits the sheet metal forming the head of the drum to be crimped about four sides of the octagonal wall and into the recess, but on the other four alternate sides of such wall, where the channels or grooves 16 are placed, the metal can be left uncrimped, so 90

that air may enter the octagonal opening and pass into the drum through the channels 16. In other words, the connection between the ring 15 and the top of the drum is such that while the ring is securely held in place, the bent edge of the metal of the top does not obstruct the air passageways 16.

An inverted annular channel or trough 20 is positioned in the under side of the top ring 15, and as best shown in Fig. 3, upwardly extending arms 21 of a cup-shaped baffle 22 extend into the upper channel while legs 23 of the same baffle project into the trough 11. This arrangement enables the baffle to be rigidly secured to the shell and top ring, as will be the case in the construction shown in Figs. 1, 2 and 3, or to rotate within the shell, as will be explained in connection with Figs. 4, 5 and 6.

In each form of the invention there is a valve employed to close the lower end of the shell to prevent refilling of the receptacle, but the valve in the beginning is retained in open position so that the vessel may be filled through the top ring 15, and the inflowing liquid will flow between the arms 21 of the baffle, then through the annular space 24 between the baffle and shell, and thence between the legs 23, and finally through the bottom opening of the shell.

This valve is designated 25 in Fig. 1, 25a in Fig. 3, and 25c in Figs. 4, 5 and 6.

The means for initially retaining the valve in open position in Figs. 1 and 2 consist of a resilient metal yoke or inverted U-shaped member 26 which extends diametrically across the cup forming the baffle, and has hook legs 27 which extend beneath the valve 25 so as to normally prevent a spring 28 from forcing the valve on to its seat 29.

The closing plug 30 for the drum, is employed to actuate this valve retainer, and it will be observed that for this purpose, the threaded skirt 31 is slightly longer than usual, whereby when the plug is screwed into the threaded portion 32 of the top ring, its skirt will move the diametrical portion of the retainer downwardly as indicated in dotted lines, whereby the hook legs will be removed from beneath the valve and the spring 28 will force the latter to its seat.

From this it will be understood that while the receptacle is being initially filled, the retainer 26 will prevent the valve from closing, but when the sealing plug 30 is attached, it will function to move the retainer so that the latter will release the valve and the valve will seat. From that time on, the spring 28 will seal the device against refilling, but of course, the spring has insufficient strength to prevent liquid from flowing outwardly when it is pumped in the usual way.

It is preferred that a gasket 33 be used in connection with the plug 30 to close any exit 65 from the air grooves 16 to prevent any out-

ward seepage of oil through these grooves while the receptacle is in transit.

If preferred, as shown in Fig. 3, the valve 25a may be initially held off its seat by a bow spring 26a which is positioned beneath the valve and has legs 27a resting on the lower portion of the shell. In this case, the valve will be spaced slightly from the bottom 22a of the baffle, and will be formed of magnetic material, and when magnetic force is exerted upwardly through the opening in the top of the device, the valve 25a will rise slightly and the legs 27a, under their own resiliency, will spring toward one another so that the retainer 26a will drop into the pipe 10a, and then the spring 28a will force the valve to its seat, when the magnetic force is released.

As shown in Figs. 4 to 6 inclusive, the valve can be initially retained off its seat by distortable arms or pins 40 which project inwardly from the wall of the shell and initially support the valve 25c. In this event, the baffle 22b will be rotatably arranged within the shell, and consequently, when the baffle is rotated about the axis of the shell, its legs 23a will strike the pins and bend the same out of valve obstructing position, as indicated in Fig. 5. Then the spring 28b will act to seat the valve.

The baffle in this instance can be rotated by any suitable magnetic tool inserted through the top of the device, or the baffle may have its cylindrical wall provided with inwardly pressed protrusions 22c that may be engaged by any special turning tool built for the purpose.

As illustrated in Fig. 6, any of the forms of the device described may be employed in connection with a conventional suction pump provided the latter is equipped with an improved adapter. As illustrated in this figure, a conventional pump 50 has a suction pipe 51, and this pipe is provided at its lower end with a nut 52 that is externally threaded so that it may be screwed into the threaded portion 32 of the top ring. Another threaded collar 53 is secured to the base portion of the pump and bears on the sealing gasket 33, after the sealing plug is removed. With this arrangement, the external passageway 54 of the pump communicates by way of the grooves 16 shown in Fig. 7 with the interior of the receptacle, so that air may flow through the pump into the receptacle 120 while oil is withdrawn from the latter through the pipe 10 and past the valve 25c.

In all of my constructions, as the valve 25, 25a, 25c is supported by the shell or cup 8 secured to the top 17 of the drum, the down pipe 10, 10a may be made of a thin tin tube which may be of inexpensive and light construction. Furthermore, the arrangement of the valve at the top of the drum eliminates the necessity of employing a suction 130

the passageway in a direction toward the lower end of the tube.

6. A non-refillable receptacle having a top and a bottom, a ring rigidly secured to said top and having an opening therein for use in discharging the contents of the receptacle, a down tube in the receptacle in alignment with said opening and extending from a point adjacent to the bottom of said receptacle to a point adjacent the top of the receptacle, a hollow cup rigidly secured to the down tube, said cup having an upset portion in interlocking engagement with the ring and being arranged between the ring and tube and functioning to maintain said tube in its operative relation with respect to said top without the presence of additional supporting means at the lower end of the down tube, a check valve arranged in the cup for preventing refilling of the receptacle through the down tube, and a guard baffle above the valve to prevent tampering with the latter.

7. A non-refillable drum having a top and bottom, a ring rigidly secured to the top and having an opening therein for use in discharging the contents of the receptacle, said ring also having internal screw threads for use in attaching a dispensing pump thereto, said bottom having a sump arranged directly below said opening, a down tube in the drum in alignment with said opening and extending into said sump, a hollow cup intervening between said ring and said tube functioning to maintain said tube in its operative relation with respect to said top without the presence of additional supporting means at the lower end of the down tube, means within the drum for securing the cup to the ring, and a check valve in said cup for preventing refilling of the receptacle through said down tube.

In testimony whereof, I hereto affix my signature.

FRANK A. TALBOT.

valve in the pump, as my valve is arranged sufficiently close to the pump to serve as a suction valve for the same. Moreover, as the down tube does not have to carry a valve, and therefore may be made of light material, it is unnecessary to anchor its lower end to the bottom of the drum where it extends into the sump, (Fig. 6).

In the last mentioned figure, the construction is also such that the pump may face in any direction relatively to the drum. As advertising matter is usually placed at one side of such a drum, it is desirable that the pump face in that direction. In accordance with my invention, the member 52 can be screwed downwardly to a desired depth within the ring 32, and then the pump may be turned to face the pump in the desired direction. Afterwards, the nut 53 can be screwed down on to the gasket 33 to make a tight joint and to prevent the pump from accidentally moving out of proper position relatively to the advertising matter on the drum. In other words, my parts 51, 52 and 53 are of such construction relatively to the drum, that they in effect form a swivel connection for securing the pump to the drum.

From the foregoing it is believed that the various forms of the invention which have been illustrated may be clearly understood, and it is manifest that changes may be made in the details disclosed, without departing from the spirit of the invention, as expressed in the claims.

What is claimed and desired to be secured by Letters Patent is:

1. A component or unit constituting an operative portion of a non-refillable container comprising a drum top, a ring secured to said top and provided with an opening, a down tube below the top in alignment with said opening, means intervening between said top and said tube functioning to maintain said tube in its operative relation with respect to said top without the presence of additional supporting means at the lower end of the down tube, said means being of greater diameter than the opening to prevent withdrawal of said means and down tube through said opening said ring, means and down tube forming a passageway, and a check valve in the passageway adjacent to the upper end of the tube for preventing flow of liquid through the passageway in a direction toward the lower end of the tube.

2. A non-refillable drum having a top and bottom, a ring rigidly secured to the top and having an opening therein for use in discharging the contents of the receptacle, a down tube in the drum in alignment with said opening, a hollow cup intervening between said ring and said tube functioning to maintain said tube in its operative relation with respect to said top without the presence of additional supporting means at the lower end

of the down tube, said cup being of greater diameter than the opening to prevent withdrawal of the cup and down tube through said opening and a check valve in said cup for preventing refilling of the receptacle 70 through said down tube.

3. A component or unit constituting an operative portion of a non-refillable container comprising a drum top, a ring secured to said top and provided with an opening, a down tube below the top in alignment with said opening, means intervening between said ring and said tube functioning to maintain said tube in its operative relation with respect to said top without the presence of additional supporting means at the lower end of the down tube, said ring, means and down tube forming a passageway, said means being of greater diameter than the opening to prevent withdrawal of said means and the down tube through said opening and a check valve in the passageway adjacent to the upper end of the tube for preventing flow of liquid through the passageway in a direction toward the lower end of the tube.

4. A non-refillable receptacle having a top and a bottom, a ring rigidly secured to said top and having an opening therein for use in discharging the contents of the receptacle, a down tube in the receptacle in alignment with said opening and extending from a point adjacent to the bottom of said receptacle to a point adjacent to the top of the receptacle, a hollow cup rigidly secured to the down tube and to the ring, said cup being arranged between the ring and tube and functioning to maintain said tube in its operative relation with respect to said top without the presence of additional supporting means at the lower end of the down tube, said cup being of greater diameter than the opening to prevent withdrawal of the cup and down tube through said opening a check valve arranged in the cup for preventing refilling of the receptacle through the down tube, and a guard baffle above the valve to prevent tampering with the latter.

5. A component or unit constituting an operative portion of a non-refillable container comprising a drum top, a ring secured to said top and provided with an opening, a down tube below the top in alignment with said opening, means intervening between said top and said tube, comprising an upset portion in interlocking engagement with the ring, said means functioning to maintain said tube in its operative relation with respect to said top without the presence of additional supporting means at the lower end of the down tube, said ring, means and down tube forming a passageway, and a check valve in the passageway adjacent to the upper end of the tube for preventing flow of liquid through 130
